FURNACE REGULATOR

Thomas J. Long, South Bend, Ind.

Application April 30, 1934, Serial No. 723,095

7 Claims. (Cl. 236—16)

This invention relates to improvements in furnace regulators the character of which is similar in some respects to that set forth in Letters Patent No. 1,698,551, issued to me January 8, 1929. The object of the present invention is to provide a simplified construction for automatic operation of the draft and check dampers of a heating furnace controlled by a thermostat, and also to afford means for adjusting the apparatus from a point remote from the furnace. A further object is to provide a simple means operated by the fuel door and associated with the damper controlling means so arranged as to cause the dampers to close when the fuel door is opened. Other objects and advantages of the invention will appear hereinafter.

An illustrative embodiment of the invention is shown in the accompanying drawing, in which:

Fig. 1 is a side elevation of the head portion of a thermostat and its complemental operable parts, several portions thereof being cut away;

Fig. 2 is a plan view projected from Fig. 1;

Fig. 3 is a side elevation of the tail end portion of the thermostat and a supporting extension attached thereto, partly in section;

Fig. 4 is a perspective view of the head of the thermostat and its complemental operating parts shown in idling position; and

Fig. 5 is a diagram showing the apparatus applied to a furnace.

The illustrative embodiment of the invention consists of a head 1 from which extends a beam 2 constituting an expansion member and in which is longitudinally disposed a rod 3 that is definitely secured at one end in the tail of the beam by means of an anchor pin 4. The beam is formed of metal of greater expansible properties than that of the rod so that as the temperature of the beam and rod fluctuates more or less movement of the forward end of the rod 3 relative to the head 1 takes place.

An actuating arm 5 is secured in the head 1 on a transversely disposed pin 6, and the forward end of the rod 3 is secured in the hub of the arm 5 by means of a transversely disposed pin 7 located at a point spaced below the pin 6 on which the arm is mounted. Thus, the arm is caused to swing upwardly or downwardly dependent upon the fall or rise in temperature of and unequal contraction or expansion of the beam 2 and its contained rod 3. The actuating arm has at its outer end a pulley block 8 having mounted therein upon a transversely disposed pin 9 a pair of sheaves 10 and 11 hereinafter referred to.

In the head 1 is pivotally supported upon aligned pins 12 a rock frame 13 having a vertically disposed opening 14 through which the arm 5 extends and has free vertical movement. In the upper end of the frame 13 is mounted upon a trans-

versely disposed pin 15 a pair of sheaves 16 and 17, and a pair of corresponding openings 18 are made in said frame through which access is had to said sheaves. The sheave 16 in the frame 13 and the sheave 11 in the block are alined with each other as are also the sheaves 10 and 17, which alinement are maintained throughout the movements of the actuating arm 5 and the rock frame.

In use the expansion beam 2 is inserted into the hot air bonnet 19 of a furnace 20 with the head 1 positioned exteriorly on the front thereof. The tail end of the beam is preferably provided with an extension supporting rod 21 that projects through the wall of the bonnet opposite the head. The extension rod is of suitable length as to project through the wall of the bonnet opposite the head so that the beam is held in proper position.

The furnace to which the invention is applicable has a fire door 22 through which fuel is supplied; a draft damper 23 for admission of air necessary for combustion of the fuel supplied through the fire door; and a smoke pipe 24 through which the products of combustion from the furnace are expelled and which is provided with a check damper 25 as in the usual practice.

The draft damper 23 is connected with the check damper 25 by means of a chain or cable 26—26' that is strung from the draft damper over the sheave 11 on the arm 5, from thence under the sheave 16 in the frame 13, over an adjusting drum 27, and from thence under the sheaves 17 and 10, and then over suspended pulleys 28 and 29 to the check damper 25. The cable 26—26' is of such limited length that when the apparatus is in normal operating position upon travel of the cable the draft and check dampers are actuated so that when one is open the other is closed, and vice versa according to the direction of travel. When the frame 13 is in normal operating position, as shown in Fig. 1, by adjustably turning the drum 27 in one direction or the other the cable 26—26' is moved so that the draft and check dampers are accordingly adjusted.

The drum 27 is of any suitable construction and is conveniently supported upon the floor 30 above the furnace, or at a more remote location in the building to suit the convenience of the operator in making adjustments without necessity of attending the furnace.

The upper end of the rock frame 13 has attached thereto at one side thereof, by means of a screw 31, another cable 32 that extends pendently, passes through a pulley 33 secured to the furnace at a point thereon adjacent the hinged side of the fire door 22, and is connected with the latch 34 on the fire door. By this means when the fire door is closed the rock frame is held down.

upon the head 1 in operating position as shown in Fig. 1. When the fire door is swung to open position the pull on the cable 32 is relaxed which permits the rock frame 13 to swing outwardly 5 to the position shown in Fig. 4 which occasions slackening of the cable 26-26', whereupon both the draft and check dampers close which is desirable especially when fuel is supplied to the furnace as then air is drawn through the fire 10 door opening into the furnace and out with the product of combustion through the smoke pipe. When the fire door is again closed the rock frame is returned to its operating position and the slack of the cable 26-26' is taken up.

15 Upon firing the furnace the heat generated thereby is imparted to the air in the hot air bonnet which is distributed to desired points through pipes 35 connected therewith, and the temperature of the expansion beam is raised more or less 20 accordingly which causes downward movement of the actuating arm 5 and consequent travel of the cable 26-26' correspondingly. Thus, the draft damper 23 is permitted to close while the check damper 25 is raised. As the fire in the furnace moderates the temperature of the air and the expansion beam in the bonnet correspondingly falls causing the actuating arm 5 to rise, whereupon the draft damper 23 is drawn open while the check damper 25 is permitted to close which has 25 the effect of reviving combustion of fuel in the furnace. In this manner the temperature of the air in the bonnet is regulated. By manipulating the regulating drum 27 the cable 26-26' is adjustably moved with respect to the actuating arm 30 so that thereafter the dampers are automatically opened or closed oppositely with respect to each other as the temperature within the bonnet varies from the degree as predetermined.

I claim:

- 40 1. In apparatus for automatically controlling the draft and check dampers of a furnace, an expansion beam posed within the hot air bonnet of a furnace having a head disposed exteriorly with respect to said bonnet, a rod extending longitudinally in said beam composed of metal of less susceptibility to expansion when heated than said beam, one end thereof being secured in the tail end of said beam, an actuating arm having sheaves in one end thereof and pivotally supported at its opposite end in said head and pivotally connected with said rod, an extension to support said beam in operating position in said bonnet, a rock frame pivotally connected at one end thereof with said head, and having sheaves in its other end alined with the corresponding sheaves in said arm, an adjusting drum supported above said furnace, a cable engaging said sheaves connected at one end to the draft damper of the furnace, and at its opposite end with the check damper therefor, said cable being operatively related with said actuating arm, rock frame and adjusting drum, and another cable operatively connecting the fire door of the furnace with said rock frame disposed to hold the rock frame 45 in operative position when said door is closed.
- 50 2. In apparatus for controlling automatically the draft and check dampers of a furnace, a thermostat disposed in the hot air bonnet of said furnace, an arm pivoted in the head of said thermostat and actuated thereby, a rock frame pivoted in said head, a supported adjusting drum more or less remote from said furnace, and a cable connecting the draft and check dampers of said furnace and operably engaged by said arm, frame and drum.
- 55 3. In apparatus for controlling automatically the draft and check dampers of a furnace, a thermostat disposed in the hot air bonnet of said furnace, an arm pivoted in the head of said thermostat and actuated thereby, provided with sheaves in its free end, a rock frame pivoted in

said head provided at its free end with sheaves alined with the sheaves in said arm, a supported adjusting drum more or less remote from said furnace, a cable engaging said sheaves and connected with said drum to be adjustably moved thereby, one end of said cable being connected with the draft damper of the furnace and the opposite end of said cable being connected with the check damper therefor, and another cable operatively connecting the fire door of the furnace 10 with said rock frame disposed to hold the rock frame in operative position when said door is closed.

3. In apparatus for controlling automatically the draft and check dampers of a furnace, a 15 thermostat disposed in the hot air bonnet of said furnace, an arm pivoted in the head of said thermostat and actuated thereby provided with sheaves in its free end, a rock frame pivoted in said head provided at its free end with sheaves alined with the sheaves in said arm, a supported adjusting drum more or less remote from said furnace, and a cable engaging said sheaves and connected with said drum to be adjustably moved thereby, one end of said cable being connected with the draft damper of the furnace and the opposite end of said cable being connected with the check damper therefor.

4. In apparatus for controlling automatically the draft and check dampers of a furnace, a 20 thermostat disposed in the hot air bonnet of said furnace, an arm pivoted in the head of said thermostat and actuated thereby, a rock frame pivoted in said head, a supported adjusting drum more or less remote from said furnace, a cable connecting the draft and check dampers of said furnace and operably engaged by said arm, frame and drum, and a connection between the fire door of the furnace and said frame disposed to hold 25 said frame in operative position when said door is closed.

5. In apparatus for controlling automatically the draft and check dampers of a furnace, a 30 thermostat disposed in the hot air bonnet of said furnace, an arm pivoted in the head of said thermostat and actuated thereby, a rock frame pivoted in said head, a supported adjusting drum more or less remote from said furnace, and a cable connecting the draft and check dampers of said furnace and operably engaged by said arm, frame and drum.

6. In apparatus for automatically controlling the draft and check dampers of a furnace, a 35 thermostat having an arm actuated thereby, a frame mounted to have pivotal movement, a supported adjusting drum more or less remote from said furnace, a cable connecting the draft and check dampers of said furnace and operatively engaged by said arm, frame and drum, and a connection between the fire door of the furnace and said frame disposed to hold said frame in operative position when said door is closed.

7. In apparatus for automatically controlling the draft and check dampers of a furnace, a 40 thermostat having an arm actuated thereby, a frame mounted to have pivotal movement, a supported adjusting drum more or less remote from said furnace, and a cable connecting the draft and check dampers of said furnace and operatively engaged by said arm, frame and drum.
